UNITED STATES PATENT OFFICE.

CHARLES PEARSON, OF CHICAGO, ILLINOIS, ASSIGNOR TO INTERNATIONAL HARVESTER COMPANY, A CORPORATION OF NEW JERSEY.

TONGUE SUPPORT.

1,419,303.

Specification of Letters Patent. Patented June 13, 1922.

Application filed June 25, 1918. Serial No. 306,561.

To all whom it may concern:

Be it known that I, CHARLES PEARSON, a citizen of the United States, residing at Chicago, in the county of Cook and State 5 of Illinois, have invented certain new and useful Improvements in Tongue Supports, of which the following is a full, clear, and exact specification.

This invention relates to tongue supports, 10 and more particularly to wheeled tongue supports for agricultural machines.

It is becoming more and more common to support the tongues of agricultural machines such as mowers, during their operation 15 in order to sustain the weight of the tongue and the machine and to take this weight from the horses used to propel the machine. Wheeled tongue supports are, moreover, provided to facilitate the turning 20 of the machine, and in connection with this feature it is desirable that the connection between the wheel and the tongue be so designed that the wheel will normally be retained in a uniform position of adjustment, 25 or in a position corresponding to the position of the main wheels of the machine.

It is also desirable that this supporting means for the tongue be made resilient in order to accommodate the various positions 30 assumed by the machine in operation in a field.

It has been found that harvester implement tongues are subjected to a torsional strain during the operation of the machine, 35 the strain being caused by the tilting of the axle of the machine, and therefore it is desirable that means be provided for overcoming this torsional strain.

The present invention, therefore, has for 40 its objects to provide supporting means for the tongue of agricultural machines and machines of that character, and moreover, to provide supporting means that will resiliently support the tongue and will automatically return its tongue to a normal position of adjustment.

A further object is to so connect the support with the tongue that the support, such for instance as a castor wheel, will be normally retained in a position of steering position corresponding to the path of travel of the main wheels of the machine.

A still further object is to provide means for returning the castor wheel or other support to this normal position of steering

adjustment after the castor wheel has been turned on its axis, as for instance, when the machine is turned out of its normal direction of travel.

A still further object is to so connect the axle of the castor wheel with the pivot axis on which it is swiveled, that the normal direction of travel of the castor wheel may be varied in order to accommodate the support to different degrees of side draft. 65

With the above objects in view, my invention consists briefly of a castor wheel support, which is resiliently connected with the tongue of the machine whereby the tongue is automatically returned to a normal position of vertical adjustment after being changed from that position to different positions of adjustment. The invention also includes means for normally maintaining the castor wheel in a definite position of adjustment with respect to the direction of travel of the castor wheel, this means being so constructed that the castor wheel will automatically change from this normal position when the machine is turned out of its normal path of travel, but will be automatically returned when the machine is again propelled in its normal direction of travel. In working out my invention I have also provided means co-operating with the tongue support and engaging the frame of the machine for preventing and overcoming any torsional strain on the tongue. 75

Referring to the drawings, wherein one embodiment of the invention is shown— 90

Fig. 1 is a top plan view of a mowing machine having my improved tongue support thereon;

Fig. 2 is a side elevation of the construction shown in Fig. 1; 95

Fig. 3 is a sectional view in elevation and on an enlarged scale, showing the resilient connection between the tongue support of the brackets secured to the tongue;

Fig. 4 is a rear elevational view of the castor wheel support and its pivotal mounting;

Fig. 5 is a detail view, partly in section, showing the adjustable connection between the castor wheel and its vertical pivot; and 105

Figs. 6 and 7 illustrate in plan and elevation the construction of one of the cam members which normally retain the castor wheel in a definite direction of travel.

In illustrating my improved construction 110

of castor wheel tongue support, I have shown this support in connection with a mowing machine, but it should be understood that while this support is particularly adapted 5 for mowing machines, it is also adapted to other agricultural machines, and that the type of machine illustrated has been chosen merely for the purpose of showing one practical embodiment of the invention. The 10 mowing machine illustrated is of the common type of machine and comprises a frame 10, pivotally supported on an axle 11, which in turn is carried by the usual main wheels 12 of the mower. The driving shaft for the 15 cutting mechanism is journaled in a forwardly extending casing 13, preferably formed integral with the machine frame. The cutting apparatus 14 is connected to the frame by means of a coupling bar 15 and a 20 drag bar 16 in the usual manner. Suitable driving connections for the cutter bar are provided, but these connections have been omitted from the showing as they constitute no part of the invention herein claimed. A 25 tongue 17 is secured to the frame of the machine by bolts 18, and extends forwardly therefrom, being provided at its front end with the usual means for securing the horses or other draft means thereto.

30 The tongue support is connected to the tongue through a bracket 19 which is secured in any suitable manner or as by bolts 20 to the tongue. The bracket 19 is provided with two pairs of outwardly extending lugs 35 21 inclined with respect to the tongue, the lugs of each pair being provided with aligned apertures adapted to receive pivot pins 22, on which are journaled the inner ends of links 23. The links 23 are disposed parallel 40 to each other and are pivotally connected at their outer ends to lugs 24, preferably formed integral with a vertical pivot castor bracket 25. The pivot pins 25', by means of which the links 23 are connected with the lugs 24, 45 are disposed parallel to the pivot pins 22 carried by the bracket 19, this construction being clearly illustrated in Fig. 1. The vertical pivot bracket 25 is provided at its lower end with a cam member 26, having inclined 50 cam surfaces 27, these surfaces cooperating with corresponding cam surfaces on a cam member 28, illustrated in detail in Figs. 6 and 7. The member 28 has formed integrally therewith a sleeve portion 29, and the sleeve 55 portion 29 is provided with an outwardly extending lug 30 having a slot 31 adjacent its outer end and formed concentrically with the longitudinal axes of the sleeve 29 and cam member 28. The cam member 28 and 60 sleeve 29 are also provided with a central longitudinal bore 32 for the reception of the vertical pivot axle 33, upon which the castor wheel support is swiveled. The pivot bracket 25 is also provided with the corresponding 65 longitudinal bore which forms a bearing for

the axle 33. The axle 33 has formed integrally therewith at its lower end an outwardly projecting or offset arm 34, this arm in turn having formed integrally therewith a downwardly extending arm 35, and the 70 castor wheel 36 is carried by an offset axle 37, preferably formed integral with the vertically extending arm 35. The arm 34 is adjustably secured to the lug 30 on cam member 28, by bolt 38 which passes through the 75 arm 34 and through the slot 31 formed in the lug 30. By means of this adjustable connection, the angle of the axle 37 carrying the castor wheel 36 may be adjusted with respect to the tongue or with respect to the direction of travel of the machine. As in the usual mower construction, the cutter bar is provided with a swather board at its outer end, and this board clears a path in which the grassward mower wheel travels on the 80 succeeding round of the field. Attention is here called to the fact that the castor wheel is positioned immediately in front of the main wheel, and so travels in the path cleared by the swather board. In case of side 85 draft, it may be found desirable to adjust this castor wheel so that its normal direction of travel will be slightly inclined to the main path of travel of the machine. In Fig. 90 5 I have shown two positions of adjustment 95 of the castor wheel. A cotter pin 39 is secured to the upper end of the vertical pivot axle 33, this pin preventing the axle from becoming disconnected from the bracket 25. In working out my improved castor wheel 100 support I have also provided resilient means for adjustably maintaining the castor wheel in a definite vertical position, this resilient means comprising a spring 40 secured at its inner end to a bolt 41 having a hooked end 105 portion 42, the bolt 41 being secured to an offset lug 43 carried by the bracket 19. The opposite end of the spring 40 is secured to the hooked end portion 44 of a bolt 45 which in turn is secured to an offset portion 46 110 formed on the outer end of the upper link 23. In Fig. 3 I have shown two vertical positions of adjustment of the tongue support, and from this showing the action of the 115 spring will be clear. As the castor wheel support and the tongue change their relative positions of adjustment the spring 40 is stretched, but tends to return these members to their normal positions and to maintain 120 them in this position.

As stated above in the objects of the invention, means has also been provided for preventing or overcoming the torsional strain on the tongue of the mower, and this construction will next be described. Referring particularly to Figs. 1 and 2, it will be seen that the bracket 19 is provided with a pair of rearwardly extending lugs 47, these lugs being inclined with respect to the tongue 17 and being provided with aligned 130

apertures which receive a pivot bolt 48. A bar 49 is pivotally mounted on the bolt 48 and is inclined with respect to the path of travel of the machine, the rear end of this 5 bar being offset as shown at 50. The offset end 50 of the bar 49 rests on and contacts with the upper surface of the casing 13. At its opposite end the bar 49 is provided with a substantially vertical aperture 51, which 10 receives a bolt 52 which in turn passes through an offset lug 53, preferably formed integral with the bracket 19. Bolt 52 is headed at its lower end and has an adjustable nut 52' at its upper end to provide for 15 changing the effective length of the bolt, thereby providing for the counteracting of different degrees of torsional strain on the tongue. This adjustment also provides for the attachment of the device to different 20 sizes and styles of frames. From the above description it is believed that the operation of this bar 49 will be clear, it being understood that the torsional strain of the tongue 25 tends to lift the portion of the tongue disposed on the grassward side of the machine, and to depress the portion of the tongue disposed toward the stubbleward side of the machine. As this strain is exerted and tends to twist the tongue, the rear 30 end portion 50 of the bar 49 will tend to move in a downward direction, but this tendency is counteracted by the contact of this portion of the bar with the casing 13 of the machine. Therefore, the bar 49 overcomes 35 the tendency of the tongue to twist.

In view of the fact that the operation of the various parts of the improved tongue support has been set forth in connection with the description of these parts, it is believed that further statements of operation 40 will be unnecessary.

From the above description of the construction and operation of the improved tongue support and of the means co-operating therewith for overcoming the torsional strain on the tongue, it will be seen that a simple, practical and efficient construction has been provided, and a construction whereby the castor wheel is normally maintained 45 in a definite direction of travel, is automatically returned to this direction of travel after having been deflected therefrom, is normally maintained in a definite position of vertical adjustment and is automatically returned to this position after having been moved to other positions of adjustment and whereby the tendency of the tongue to twist 50 and to be placed under torsional strain is counteracted and overcome. In connection 55 with the means for controlling the normal direction of travel of the castor wheel, means has also been provided for changing this direction, so that the direction of travel to which the castor wheel returns after being

deflected may be varied in order to overcome side draft or for any other desired reason. 65

While I have in the above specification described one embodiment of my invention and have illustrated this embodiment in connection with a particular type of machine, it should be understood that any other type of machine may be used if desired, and that changes and modifications in the construction and the arrangement of the various 70 parts of the device may be made without departing from the spirit and scope of the invention, as expressed by the following claims:

1. In combination, a mower having a 80 frame, a tongue carried thereby, supporting wheels for said frame, and a tongue support secured to said tongue in offset relation with respect thereto and disposed in the path of the grassward supporting wheel. 85

2. In combination, a mower having a frame, supporting wheels thereof, a tongue carried by said frame, a bracket carried by said tongue and a castor wheel resiliently connected to and in advance of said bracket 90 and disposed in the path of the grassward supporting wheel.

3. In combination, a tongue, a castor wheel mounted in a castor bracket, a plurality of movable link connections between 95 said castor bracket and said tongue and resilient means for determining the vertical position of said castor wheel with respect to said tongue.

4. In combination, a tongue, a bracket 100 carried thereby, a plurality of parallel links pivotally connected to said bracket, a castor wheel pivotally connected to the outer ends of said links and resilient means connecting one of said links with said bracket. 105

5. In combination, a tongue, parallel links operatively connected to said tongue, a vertically disposed bracket operatively connected to said links at their outer ends, a castor wheel swivelly connected to said 110 bracket and means for normally retaining said castor wheel in a definite position with respect to said bracket.

6. In combination, a tongue, a support for said tongue, including a bracket fixed to said 115 tongue and movable vertically with respect thereto, a vertical pivot axle swiveled in said bracket, a castor wheel operatively connected to said pivot axle and means for maintaining said pivot axle and castor wheel 120 in a definite lateral adjustment with respect to said bracket.

7. In combination, a tongue, a vertically disposed bracket operatively connected thereto, a castor wheel swivelly connected to 125 said bracket, means for normally retaining said bracket in a fixed position of adjustment with respect to said castor wheel and

means for adjusting said castor wheel laterally with respect to said bracket in a manner to vary said fixed position of adjustment.

8. A tongue support including in combination a vertically disposed bracket, a vertical pivot axle swiveled in said bracket said bracket movable vertically with respect to said tongue and means carried by said pivot axle and said bracket for releasably maintaining said pivot axle in a fixed relation with respect to said bracket.

9. A tongue support including in combination a vertically disposed bracket, a pivot axle swiveled therein, a castor wheel operatively connected to said axle, a cam member carried by said bracket and a coacting cam member adjustably connected to said axle.

10. In combination, a mower having a frame, a tongue carried thereby, and adjustable means carried by said tongue and engaging said frame for preventing torsional strain on said tongue in a predetermined direction.

11. In combination, a machine having a frame, a tongue carried by said frame and a pivoted member operatively connected to said tongue and engaging said frame for preventing torsional strain on said tongue in a predetermined direction.

12. In combination, a machine frame, a tongue carried thereby, a bracket carried by said tongue and a bar pivoted on said bracket and engaging said frame for counteracting torsional strain on said tongue in a predetermined direction.

13. In combination, a machine frame, a tongue carried thereby, a bracket carried by

said tongue and means pivoted on said bracket and adjustably engaging said frame for counteracting torsional strain on said tongue in a predetermined direction.

14. In combination, a machine having a forwardly projecting frame member, a tongue operatively connected to said machine and a bar carried by said tongue and positioned edgewise for engaging said forwardly projecting frame member for counteracting torsional strain on said tongue in a predetermined direction.

15. In combination, a mower having a frame, a tongue carried thereby, a bracket carried by said tongue, a castor wheel operatively connected to said bracket and means comprising a bar carried by said bracket and engaging said frame for counteracting torsional strain on said tongue in a predetermined direction.

16. In combination, a mower having a frame, a tongue carried thereby, a bracket secured to said tongue, a castor wheel resiliently connected to said bracket and a lever pivoted to said bracket and engaging said frame at the rear end of said lever and engaging said bracket at the front end of said lever for preventing torsional strain on said tongue in a predetermined direction.

17. In combination, a tongue, a bracket carried thereby, a plurality of links disposed diagonally with respect to said tongue and pivotally connected to said bracket, a castor wheel operatively connected to the outer ends of said links and resilient means connecting both of said links.

In testimony whereof I affix my signature.
CHARLES PEARSON.
